United States Patent Office

Des. 216,831

Patented Mar. 10, 1970

216,831

CIGARETTE LIGHTER

Kenjiro Goto, Tokyo, Japan, assignor to Mansei Kogyo Kabushiki Kaisha, Saitama-ken, Japan

Filed Jan. 7, 1969, Ser. No. 15,237

Term of patent 7 years

Int. Cl. D27—05

U.S. Cl. D48—27

FIG. 1

FIG. 2

FIG. 3

FIG. 4

FIG. 5

FIG. 6

FIG. 1 is a top plan view of a cigarette lighter showing my new design:

FIG. 2 is a left side elevation thereof;

FIG. 3 is a front elevation thereof;

FIG. 4 is a right side elevation thereof;

FIG. 5 is a bottom plan view thereof; and

FIG. 6 is a perspective view of the lighter.

I claim:

The ornamental design for a cigarette lighter, substantially as shown.
